ATTORNEY,

UNITED STATES PATENT OFFICE.

PAUL PERSSON, OF CHICAGO, ILLINOIS.

DESIGN FOR A GARBAGE-RECEPTACLE.

44,110.

Specification for Design.

Patented May 27, 1913.

Application filed January 28, 1913. Serial No. 744,773. Term of patent 14 years.

To all whom it may concern:

Be it known that I, PAUL PERSSON, a citizen of the United States of America, residing at Chicago, in the county of Cook and State of Illinois, have invented a new, original, and ornamental Design for Garbage-
Receptacles, of which the following is a specification, reference being had to the accompanying drawings, forming part thereof.

The figure is a perspective view of the garbage receptacle.

I claim:

The ornamental design for a garbage receptacle, as shown.

PAUL PERSSON.

Witnesses:

ARTHUR J. RAY,
CHAS. W. BUELL.
